UNITED STATES PATENT OFFICE

MAXIMILIAN SANDIG AND DAVID BUCK, OF VIENNA, AUSTRIA

TOOTHRUSH

Application filed August 21, 1929. Serial No. 387,459.

The invention consists as follows: Two reference numeral 3. The curved part 14 brushes are arranged on one handle, one having the bristles on the concave, the other on the convex side; this improved style of tooth-brushes can be closed, so that it can be kept practically secured from dirt by a single cover enveloping both brushes.

With tooth-brushes made in accordance to the present specification, the horizontal movement of the cleansing surfaces of the brush, so harmful to the teeth, and hitherto required in tooth-brushes, is avoided. The cleansing of the teeth is performed with this modern, improved tooth-brush by a vertical movement of the same, the tooth-brush being formed in such manner that the teeth can be cleaned, both front and back, without reversing the brush. The cleansing of teeth by a vertical movement of the tooth-brush has the great advantage that the gums are thus protected and not injured by the brush. Then again, owing to the unevenness of the teeth, which are in a vertical direction, several parts are not reached when brushed horizontally and cannot be cleansed thoroughly.

Food rests and tartar is deposited on those parts of the teeth not cleansed by tooth-brushes that worked horizontally and the teeth thus suffer injuries and disorders. Besides that, horizontal brushing, or polishing is harmful to the tooth enamel, as experience has taught. Moreover, by brushing teeth in horizontal direction, a pressure is exerted perpendicularly on the axes of the roots of the teeth, loosening them, especially in the case of elderly people, and producing toothache.

The object of the invention is illustrated by the accompanying drawing, in which

Fig. 1 is an elevation, partly in section of a brush embodying our invention;

Fig. 2 is a plan view of one of the brushes shown in Fig. 1; and

Fig. 3 is a plan view of the other of the brushes shown in Fig. 1.

On the upper end of a multi-part handle composed of the members 16 and 17 and particularly on the upper part of a curved portion 14 of the handle member 16 is a curved piece 4 with bristles on the concave side thereof. These bristles are indicated by the

55 reference numeral 3. The curved part 14 of the handle 16 is so bent that one can work in a practical manner without touching the chin or nose. The other handle member 17 lies substantially parallel to the handle member 16 and has a curved portion 15 at its upper end as clearly shown in Fig. 1, and this curved portion is provided with a curved piece 7, having on its convex side bristles 11. The two curved portions 4 and 7, provided 60 with the bristles 3 and 11 respectively, are so arranged with respect to each other that the directions of the bristles are identical, that is, the bristles of the two curved parts are turned toward the user. In the case of 65 the curved piece 7, provided with bristles on the convex side, the brush formed by such bristles is so shaped that the bristles are longer in the middle than at the sides, as is clearly shown in Fig. 2. This arrangement is 70 important because, supposing that the curved portion 7 is formed according to the arrangement of the human teeth, an independent and more powerful cleansing of the one half is 75 possible without simultaneously treating the other half.

For the purpose of keeping and transporting the brush structure more easily and simply and to pack it better when traveling, the handle portions 16 and 17 are pivotally 80 mounted to each other by a stud 18, so that for cleansing purposes the portions 16 and 17 may lie in alignment with each other and when it is necessary to transport the same, they are brought into substantial parallelism 85 with each other, as shown in Fig. 1. Thus one cover may be used to protect both brush surfaces.

We claim:

1. A toothbrush comprising two handles, 90 one handle at its free end being provided with a concavely curved brush, the other handle being provided at its free end with a convexly curved brush, said first-named brush being of greater overall dimensions as compared with said second-named brush, and said brushes each extending transversely of the length of their respective handles, and means for pivotally interconnecting said handles adjacent their opposite ends to 100

cate the convexly curved brush below and within the outline of said concavely curved brush.

2. A toothbrush comprising two handles, one handle at its free end being provided with a concavely curved brush, the other handle being provided at its free end with a convexly curved brush, said first-named brush being of greater overall dimensions as compared with said second-named brush, and said brushes each extending transversely of the length of their respective handles, and means for pivotally interconnecting said handles adjacent their opposite ends to locate the convexly curved brush below and within the outline of said concavely curved brush, said handles being substantially rectangular at their said opposite ends and substantially correspondingly curved at respective portions intermediate their ends.

3. A toothbrush comprising two handles, one handle at its free end being provided with a concavely curved brush, the other handle being provided at its free end with a convexly curved brush, said first-named brush being of greater overall dimensions as compared with said second-named brush, and said brushes each extending transversely of the length of their respective handles, and means for pivotally interconnecting said handles adjacent their opposite ends to locate the convexly curved brush below and within the outline of said concavely curved brush, said handles being substantially rectangular at their said opposite ends and substantially correspondingly curved at respective portions intermediate their ends in a direction toward and substantially centrally of the free ends of said concavely curved brush.

In testimony whereof we have signed this specification this 5th day of August, 1929.

MAXIMILIAN SANDIG.
DAVID BUCK.
